Primary Examiner — Jennifer L Watkins*Assistant Examiner* — John Patrick G Ribay(57) **CLAIM**

The ornamental design for a padded shoulder sling strap, as shown and described.

DESCRIPTION

FIG. 1 is a perspective view of a padded shoulder sling strap showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the padded shoulder sling strap where the padded shoulder sling strap is in a configuration of use;

FIG. 10 is an enlarged view of portion 10 shown in FIG. 1; and,

FIG. 11 is an enlarged view of portion 11 shown in FIG. 2. The dot-dash broken lines depict the cut lines of the enlarged portions and form no part of the claim.

1 Claim, 11 Drawing Sheets(56)
